(Cl. D44—9)

To all whom it may concern:

Be it known that I, Charles L. Fordyce, a citizen of the United States of America and a resident of New York, in the county of New York and State of New York, have invented a new, original, and ornamental Design for a Glass Cup or Article of Similar Nature, of which the following is the specification, reference being had to the accompanying drawing, forming a part thereof.

Figure 1 is a side elevational view of the glass cup or article of similar nature embodying the new design.

Figure 2 is a top plan view thereof.

I claim:

The ornamental design for a glass cup or article of similar nature, substantially as shown.

CHARLES L. FORDYCE.
